UNITED STATES PATENT OFFICE.

JEROME R. GEORGE AND JOHN W. SHEPERDSON, OF WORCESTER, MASSACHUSETTS, ASSIGNEES TO MORGAN CONSTRUCTION COMPANY, OF WORCESTER, MASSACHUSETTS, A CORPORATION OF MASSACHUSETTS.

ROLLING MILL.

Application filed April 27, 1922. Serial No. 556,866.

To all whom it may concern:

Be it known that we, JEROME R. GEORGE and JOHN W. SHEPERDSON, both citizens of the United States, residing at Worcester, in the county of Worcester and Commonwealth of Massachusetts, have invented a new and useful Improvement in a Rolling Mill, of which the following, together with the accompanying drawings, is a specification.

10 The present invention relates generally to rolling mills. The invention resides in a novel combination and arrangement of roll trains and auxiliary mill equipment adapted for the rapid and convenient reduction of ingots to a diversified product of blooms, billets, slabs and sheet bar, together with mechanical means for disposing of these products after rolling.

20 The features and advantages of the invention are fully set forth in the following description, reference being had to the accompanying drawing, wherein the single figure is a diagrammatic plan view of rolling mill apparatus combined and arranged in accordance with the invention.

25 Referring to said drawing, 1 represents the rolls of a blooming mill of any well known construction, the same serving for the preliminary reduction of large size ingots taken from a soaking pit, not shown. From the receiving table 2 of the mill, the blooms are delivered to a suitable longitudinal conveying mechanism 3, consisting preferably of a series of power driven conveyor rolls of any well known type, the same extending the entire distance intervening between the table 2 and a bloom shear 4.

30 At a plurality of intermediate points in the length of conveying mechanism 3, provision is made for the broadside movement of the material onto and off of the conveying rolls 3. One such broadside transfer mechanism is indicated diagrammatically at 5, as connecting the conveying mechanism 3 with a similar longitudinal conveying mechanism 6, out of line with the conveying mechanism 3 and consisting preferably of a series of conveying rolls of well known construction. The conveying mechanism 6 is disposed in alinement with, and is adapted to deliver to a reducing roll train 7 which serves for the production, for instance, of large size billets and slabs. The several stands of rolls of the train 7 preferably provide, in the usual

manner, a plurality of rows of differently-shaped passes, to give such variety as may be desired in the cross section of the reduced material emerging therefrom. In advance of the initial pass of the rolling mill 7 is preferably disposed a crop shear 8, which operates in a usual manner to remove the crop ends of the blooms incidental to the reduction of same to form billets or slabs.

Another broadside transfer mechanism is indicated diagrammatically at 9, the same being interposed between the conveying mechanism 3 and another longitudinal conveying mechanism 10, the latter being substantially in alinement with the conveying mechanism 6 and consisting preferably of a series of ordinary conveyor rolls. The conveying mechanism 10 is disposed in alinement with, and is adapted to deliver to a reducing roll train 11 which serves for the production, for instance, of small and medium sized billets and sheet bar. The several stands of rolls of this mill are also preferably provided with a plurality of independent rows of differently-shaped passes, to give such variety as may be desired in the cross section of the reduced material emerging therefrom. As part of the equipment of the mill 11, one or more stands of edging rolls 12, 12 may also be provided, by the use of which sheet bar of variable thickness may be rolled thereby. In advance of the initial pass of the roll train 11 is preferably disposed a crop shear 13, the same serving for the removal of the crop ends of the bars as delivered thereto by the conveying mechanism 10.

35 Said conveying mechanism 10, serving for the delivery of material to the billet and sheet bar mill 11, as above described, is so disposed with relation to the larger billet mill 7 as to constitute, in effect, the run-out of the latter; in other words, the power driven conveyor rolls of mechanism 10 may serve, when desired, for the continuous longitudinal movement of stock between the two independent roll trains 7 and 11, receiving said stock from the larger mill and advancing it for further reduction by the smaller mill. The reduced product emerging from the smaller mill may be operated upon in any manner desired, as for instance, by being cut up in a flying shear 14, suitably located in the run-out 15 of said mill, pre-

liminary to movement onto a cooling bed 16 of any well-known type. Or, if the product of roll train 11 emerges in the form of sheet bar, the same may be operated upon by rolls 17 adapted to assemble the sheets one upon the other in a stack or pile preparatory to their delivery to the cooling bed 16.

With the arrangement of mechanism above described, the product of blooming mill 1 may, if desired, be carried forward by conveying mechanism 3 without any further reduction, the same being cut into blooms, billets or slabs by the shear 4 and these pieces then brought under the action 15 of a kick-off mechanism 18 which deflects them onto suitable cooling devices, here shown as a circular series of cars 19, which are successively brought into position, by rotation, to receive successive pieces. Or, 20 if desired, such material emerging from the mill 1 which is not destined for any further reduction may be transported by conveying mechanism to a cooling bed 20, with or without action thereon by the bloom 25 shear 4.

With such of the product of blooming mill 1 as is destined for further reduction, either one of the broadside transfers 5 or 9, or both of them, are brought into operation. Such transfer mechanisms are of the usual construction, providing a series of transfer supporting skids across which the stock is moved broadside, by engagement therewith of a plurality of moving lugs or 30 projections carried, for instance, by endless chains or cables; such projections can travel in either direction to carry the stock either onto and off the rolls of conveying mechanism 3, or onto and off of the rolls of conveying mechanisms 6 and 10. As a consequence, it is possible to shift any desired part of the product of the blooming mill 1 over to the conveying mechanism 6 for further reduction by the roll train 7. Such 35 reduced product, emerging in the form of large size billets or slabs on conveying mechanism 10, may then be transferred back to conveying mechanism 3 across the skids of transfer mechanism 9, and thence carried 40 forward to shear 4 and cooling bed 20. Or, if desired, such reduced product, or any part thereof, may be subjected to further reduction by roll train 11; emerging in the 45 form of smaller billets and bars, the same 50 may be cut into commercial lengths by flying shear 14 before passage onto cooling beds 16, or in the case of sheet bar, operated upon by piling rolls 17.

Under certain circumstances, such as the 55 temporary inoperativeness of the mill 7, it may be convenient to deliver the product of blooming mill 1 direct to the reducing roll train 11, in which case the transfer mechanism 9 is employed for this purpose, thereby passing mill 7 entirely. In any

case, such transfer mechanism 5 and 9, since they operate in either direction, may be employed, when and as desired, to return to the conveying mechanism 3 any product normally destined for reduction either by roll train 7 or roll train 11, but which for any reason, as the formation of a cobble, may be prevented from entering the passes of the mills 7 or 11. In this way the arrangement of apparatus particularly lends itself to the continuous uninterrupted disposition of the product of blooming mill 1, since in the event of any emergency which necessitates the temporary stoppage either of roll train 7 or train 11, or both, it is not necessary to interrupt production; if one or the other of said roll trains is rendered inoperative, the other can be used, and if both are rendered inoperative, the product of blooming mill 1 can still be disposed on the 80 cooling bed 20 or on the cars 19.

We claim,

1. In apparatus of the class described, the combination with longitudinal conveying means for the product of a blooming mill, of a plurality of independent reducing roll trains parallel to but out of line with said conveying means, and means selectively operable to procure the further reduction of said blooming mill product by either of said roll trains, or both of them. 90

2. In apparatus of the class described, the combination with longitudinal conveying means for the product of a blooming mill, of a plurality of aligned reducing roll trains out of line with said conveying means, means for transferring said product broadside, for reduction by one or the other of said roll trains, and means for returning the reduced material from one of said roll trains to said longitudinal conveying means. 100

3. In apparatus of the class described, the combination with longitudinal conveying means for the product of a blooming mill, of a plurality of aligned reducing roll trains out of line with said conveying means, means for transferring said product broadside, for reduction by the first of said roll trains, and means selectively operable to procure further reduction of said product by another roll train, or to return same to said longitudinal conveying means. 110

4. In a apparatus of the class described, the combination with a blooming mill, of a reducing roll train out of line with the center line of said blooming mill, means operable to deliver the product of said blooming mill to said roll train, for further reduction therein, and common shearing, assembling and cooling means for the product, as delivered by said blooming mill and said roll train. 120

5. In apparatus of the class described, the combination with a blooming mill, of a reducing roll train out of line with the cen- 130

- ter line of said blooming mill, a second roll train alined with the first, means operable to deliver the product of said blooming mill to either or both of said roll trains, and 5 common shearing, assembling, and cooling means for the product, as delivered by said blooming mill and said two roll trains.
6. In apparatus of the class described, the combination with longitudinal conveying 10 means for the product of a blooming mill, of a plurality of alined independent continuous rolling mills out of line with said conveying means, means for transferring said product broadside, for reduction 15 by one or the other of said rolling mills, and means for returning the reduced material from one of said mills to said longitudinal conveying means.
7. In apparatus of the class described, 20 the combination with longitudinal conveying means for the product of a blooming mill, of a plurality of alined independent
- continuous rolling mills out of line with said conveying means, means for transferring said product broadside, for reduction 25 by the first of said rolling mills, and means selectively operable to procure further reduction of said product by another roll train, or to return same to said longitudinal conveying means.
8. In apparatus of the class described, 30 the combination with longitudinal conveying means for the product of a blooming mill, of a plurality of independent reducing roll trains out of line with said conveying means, delivery mechanism associated with each of said roll trains, and means for procuring the broadside transfer of material in both directions between each of said delivery mechanisms and said longitudinal 35 conveying means.

Dated this seventeenth day of April 1922.

JEROME R. GEORGE.

JOHN W. SHEPERDSON.
